UNITED STATES PATENT OFFICE.

GEORGE H. WHEARY, OF RACINE, WISCONSIN, ASSIGNOR TO THE HARTMANN TRUNK CO.,
OF RACINE, WISCONSIN.

TRUNK.

No. 872,874.

Specification of Letters Patent.

Patented Dec. 3, 1907.

Application filed April 12, 1907. Serial No. 367,740.

To all whom it may concern:

Be it known that I, GEORGE H. WHEARY, a citizen of the United States, residing at Racine, in the county of Racine and State of Wisconsin, have invented a new and useful Trunk, of which the following is a specification.

This invention has reference to improvements in trunks of the type known as wardrobe trunks, and its object is to provide a compact, strong and easily accessible device of this character without multiplicity or complexity of parts and which will perform the functions of an ordinary trunk and at the same time hold the various articles of wearing apparel in close and well-packed condition but readily and easily accessible as soon as the trunk is opened to expose its interior.

The invention consists essentially of a trunk body which, when closed, has the appearance of an ordinary trunk, but which when opened separates on such lines as to render all parts readily accessible. The trunk is so constructed that when in position to be opened it is to all appearances standing upon one end, while that portion of the trunk corresponding to the top of an ordinary trunk is provided with an extension overlapping that portion corresponding to the body or bottom of an ordinary trunk, which latter portion is cut away or removed to receive the extension of the top of the trunk: By this means the trunk is divided on lines permitting its apparent capacity to be much enlarged so that the body or bottom of the trunk may be provided with suitable removable receptacles for various articles, while the portion corresponding to the top of a trunk may contain racks for various articles of wearing apparel, which racks and the articles carried thereby are closely compacted when the trunk is in the closed condition, but which may be sufficiently separated for ready access when the trunk is opened for the removal of its contents.

The invention will be fully understood from the following detailed description taken in connection with the accompanying drawings forming part of this specification, in which,

Figure 1 is a perspective view, with parts broken away and in section, showing the trunk in the open position; Fig. 2 is a sec-

tion through the upper portion of the trunk when set on end and closed together, with parts shown in elevation; and Fig. 3 is an elevation of that end of the trunk upon which it rests when open.

Referring to the drawings, there is shown a trunk consisting of two portions 1-2, the portion 1 constituting what will correspond to the top of an ordinary trunk and the portion 2 corresponding to what may be termed the bottom or body portion of an ordinary trunk. The top portion 1 is hinged to the body portion 2 along one edge, as indicated at 3, and this top portion is much shallower than the body portion 2.

The front panel 4 of the top portion is of much greater width than the other panels of the top, while the front panel 5 of the body portion is much narrower than the other panels making up this body portion. The front panel 4 of the top portion extends down in front of the body portion 2 until it meets the panel 5 of the latter, and this panel 4 is provided with the usual overlapping metal strip 6 engaging over the upper edge of the panel 5 of the body portion 2.

One end of the trunk is provided with a bulged portion 7 so that the trunk cannot be made to stand on this particular end, while the other end is so constructed that the trunk may be stood up on that end; and the corresponding end of the top portion 1 as well as the corresponding end of the panel 4 are provided with rollers 8-8.

Within the body portion of the trunk and extending vertically with relation to the same when the trunk is in a horizontal position, or laterally of the same when the trunk is stood on end, are angle strips 9 of a length equal to about the depth of the panel 5. These strips 9 are arranged in pairs, one on the inside face of the panel 5 and the other on the corresponding inside face of the back of the trunk, so as to constitute supporting guideways for drawers 10 of sufficient number to occupy approximately all the space included in that portion of the body of the trunk comprising a space as far from the bottom of the trunk as is the width of the panel 5. About midway of the body portion the angle strips 9 are omitted and a partition 11 is substituted serving to support one of the drawers 10 and also strengthening this portion of the body of the trunk. Considering

the trunk as standing on end, the lowermost drawer 10 is made of sufficient size to contain a hat and therefore may be considered as a hat-box. For this purpose the front 12 of this drawer is hinged to the body portion thereof so as to be held down when the trunk is stood on end, and on the inside face of this cover 12 there is secured a cup 13 carrying a cushion 14 to which a hat may be pinned in order to maintain it in the hat compartment without injury. The cover of the hat compartment is provided with fastening flaps 15 containing snap catches of ordinary type adapted to buttons 16 on the inside walls of the compartment so that this cover may be suitably secured in place. Fast on the rear wall of the body of the trunk are a number of flaps 17, each provided with a snap fastening to engage a button 18 on each drawer 10 so that when the drawer is pushed into place the flap may be made to engage such button and the drawer may be held in the bottom portion of the trunk against accidental displacement. In order to withdraw the several drawers from the bottom portion of the trunk, each one is provided with a flap handle 19. The uppermost drawer does not reach quite to the top of the trunk, considering the latter as being on end, but a space 20 designated by the reference numeral 20 remains between the top of this drawer and the corresponding end of the trunk. Since the several drawers operate as covers for the next succeeding lower drawer, none of them are provided with covers but the uppermost one, and this one is provided with a cover 21 fastened thereto by suitable flap fastenings 22. The several drawers are intended for the reception of such articles as may properly be placed therein.

Referring now to the top portion of the trunk, it will be observed that in that end which is uppermost when the trunk is stood on end is a fixed frame 23 supported by suitable brackets 24. This frame extends away from the top portion of the trunk to a greater extent than the panel 4, and when the trunk is closed together this frame 23 enters the space 20 above the topmost drawer 10. Near the ends of the frame, extending parallel to the sides thereof, are two rods 25 designed to carry cross bars 26 shown in the drawings as provided with clips 27 but which bars may be otherwise constructed, and these bars are arranged to travel on the rods 25 in the direction of the length of the rods. The bars 26 may be used as supports for coat-hangers 28 of ordinary construction, which hangers are shown in Fig. 2 only, and various other means for holding clothing may be used in connection with the bars 26 and frame 23. Since a great variety of garment-supporting devices may be adapted for use in this particular portion of the invention, and since 65 the particular construction of such devices

forms no part of the present invention, no attempt has been made to illustrate any such devices and it suffices to say that any form of garment-supporting means may be used in this connection.

Hung from the rods 25 by clips 29 is a rectangular frame 30 extending downward a suitable distance to a point somewhat remote from what may be considered the bottom end of the trunk as viewed in Fig. 1, and this frame may be tied in place by bands 31, the ends of which are appropriately secured, one to the panel 4 and the other to that panel of the top section of the trunk that is hinged to the bottom section. 75

The supporting devices carried by the frame 23 are designed to receive various garments and when as many are placed upon the supporting devices as may be, the frame 30 is moved along the rods 25 until in firm contact with these garments, compacting them to the desired degree, and it is then held in such position by means of the bands 31. 80

Now, when the top portion of the trunk is moved to a position to close it on to the bottom portion thereof, the frame 23 will enter the space 20 and the frame 30 will come in contact with or in close relation to the drawers 10, thus holding the latter in place when the trunk is being carried from place to place. Ordinarily, when the trunk is resting upon that longer side which corresponds to the bottom of an ordinary trunk, these drawers 10 will be held in place by gravity. 90

When it is desirable to open the trunk and have access to the contents thereof, the trunk is set upon end, as illustrated in Fig. 1, and the body portion is swung around on the hinges until it is stopped by contact with the bottom portion. The drawers are all now 105 accessible, as will be readily apparent. By untying the bands 31 the frame 30 is released and the various garments carried by the hangers 28 or other supports are loosened sufficiently to be easily removable either through the frame 23 or in the space between the bottom portion of the trunk and the frame 30. 110

It will be observed that the garments, especially those contained in the top portion of the trunk, are held against displacement, and, therefore, are not liable to be damaged or mussed up during transit. It will also be observed that the frame 23 extends to such a distance from the top portion of the trunk that it would strike the front of the body portion of the trunk if the said front portion was of the usual width, and, consequently, in order to enlarge the capacity of the garment carrying portion of the trunk to that degree which is sufficient to permit the trunk to receive all the garments usually carried by a traveler and to support the same from hangers as described, this garment supporting section of the trunk is made equal in ca- 125 130

pacity to that of the ordinary top of a trunk and about half the capacity of the body of a trunk.

At the end of the top section of the trunk 5 remote from the frame 23 there is provided a box 32 which, when the top section is closed on to the bottom section will fit up to within close relation to the hat-box compartment of the trunk. The box 32 is necessarily quite 10 shallow since it will occupy the space between the free ends of the frame 30 and the corresponding end of the trunk. The box 32 may be provided with a suitable cover which, however, is not shown in the drawings, or 15 the contents of the box may be prevented from accidental removal therefrom by means of straps or tapes 33, or, in fact, any means for securing the contents of the box in place may be used.

20 I claim:—

1. A trunk comprising a body portion having one side panel and two end panels of equal width and the other side panel of less width than the first-named side panel, a top 25 portion having one side panel and the end panels of equal width and the other side panel of such greater width than the first-named side panel of the top portion as to meet the narrow side panel of the body portion 30 when the top portion is closed down on the body portion, and a garment-carrier support secured to the top portion near one end thereof.

2. A trunk comprising a body portion having the back panel and both end panels of equal width and the front panel of a width less than that of the other panels, drawers or containers within the body portion of the trunk and occupying a space commensurate 35 with the width of the front panel, a top portion having the back panel and end panels of equal width and the front panel of greater width to meet the narrow front panel of the body portion, and a garment-carrier support carried by said top portion of the trunk 40 and arranged to be moved thereby into the body portion of the trunk when the top portion is closed on to the body portion.

3. A trunk comprising a body portion having its front panel of less width than the height of said body portion, a top portion having its front panel of a correspondingly greater width to complete the front of the trunk, and a garment carrier secured to one 55 end of the top portion of the trunk and projecting therefrom to an extent coextensive with the width of the front panel of said top portion and accessible from the side adjacent to the body portion of the trunk and 60 also from the side adjacent to the extended front panel of the top of the trunk.

4. A trunk comprising a body portion having a front panel of less width than the back and end panels of said body portion, a se-

ries of drawers or compartments within said 65 body portion occupying a space between the bottom of the trunk and the top of the narrow front panel and extending from one end of the trunk to a point near the other end of the trunk, a top portion having a front panel 70 of greater width than the rear and side panels and of sufficient width to meet the narrow front panel of the body portion, and a supporting frame for garment-carriers secured to the top portion of the trunk near 75 one end thereof and of such extent of projection from said top portion as to enter the body portion of the trunk between the series of compartments and the end of the trunk near which they terminate, said garment- 80 supporting frame projecting beyond the narrow back panel of the top and accessible from the side corresponding to such narrow back panel.

5. A trunk comprising a body portion having a front panel of less width than the height of said body portion, a top portion having the front panel of sufficient width to meet the narrow front panel of the body portion, a series of drawers or compartments 90 in the body portion of the trunk and of a depth approximately that of the narrow front panel of the body portion, a supporting frame for garment-carriers fast in the top portion of the trunk near one end thereof 95 and projecting from said top portion a distance equal to the width of the front panel of said top portion, and another frame hung from the first-named frame and movable from the front thereof toward the rear end 100 thereof for compacting garments placed on the garment-carriers.

6. A wardrobe trunk comprising a body portion having a front panel of less width than that of the rear and end panels, a series 105 of drawers or compartments of a depth equal to the width of the narrow front panel and terminating at a point near one end of the body portion, a top portion having a wide front panel sufficiently extensive to meet the 110 front panel of the body portion, a frame secured to said top portion near one end thereof and projecting therefrom a distance coextensive with the wide front panel of the top portion and entering the space between the 115 series of compartments and the corresponding end of the body portion, and another frame having an extent of movement equal to the length of the first-named frame for compacting garments carried by said first- 120 named frame.

In testimony that I claim the foregoing as my own, I have hereto affixed my signature in the presence of two witnesses.

GEORGE H. WHEARY.
